UNITED STATES PATENT OFFICE.

GEORGE W. SHIEBLER, OF BROOKLYN, NEW YORK.

DESIGN FOR A HANDLE FOR SPOONS, FORKS, &c.

SPECIFICATION forming part of Design No. 17,044, dated December 28, 1886.

Application filed October 21, 1886. Serial No. 216,911. Term of patent 7 years.

To all whom it may concern:

Be it known that I, GEORGE W. SHIEBLER, of Brooklyn, in the county of Kings and State of New York, have invented a new Design for the Handles of Spoons, Forks, &c., of which the following is a specification.

This design for the handle of spoons, forks, &c., is shown in the accompanying photograph. The handle is widest at the end and tapers gradually toward the shank, and the surface of the handle is convex and its end curved, and it is ornamented on the narrower portion of the convex surface with two leaves, *a a*, with serrated edges similar to maple or oak leaves, and with Japanese chrysanthemum-flower designs at *b b*, in relief, the same having long and gracefully falling leaves, as shown. These chrysanthemum flowers *b b* are adjacent to each other and of varying size, and each extends across the convex tapering handle near the broader end. There are stems connecting the leaves *a a* and flowers *b b*, and the convex surface of the handle between the flowers, leaves, and stems is ornamented with groups of parallel lines running in different directions, in imitation of basket-work. The leaves, flowers, and stems may be brought out into bold relief by darkening or oxidizing the background.

I claim—

1. The ornamental design for handles of forks, spoons, and similar articles, consisting in the design in relief of the adjacent Japanese chrysanthemum flowers of varying size, and each extending across the convex tapering handle near the broader end, and the oak and maple leaves on the narrower portion of the handle, substantially as described and represented. 30

2. The ornamental design for handles of forks, spoons, and similar articles, consisting in the design in relief of the adjacent Japanese chrysanthemum flowers of varying size, and each extending across the convex tapering handle near the broader end, and the oak and maple leaves on the narrower portion of the handle, the stems connecting the leaves and flowers, and an ornamental background in lines in imitation of basket-work, substantially as described and represented. 35

Signed by me this 16th day of October, 1886.

GEO. W. SHIEBLER. [L.S.]
